UNITED STATES PATENT OFFICE.

ABRAM S. KIRSHNER, OF PHILADELPHIA, PENNSYLVANIA.

APPARATUS FOR EXTRACTING LIQUIDS.

Application filed August 24, 1921. Serial No. 494,766.

To all whom it may concern:

Be it known that I, ABRAM S. KIRSHNER, residing at Philadelphia, county of Philadelphia, and State of Pennsylvania, a citizen of the United States, have invented certain new and useful Improvements in Apparatus for Extracting Liquids, of which the following is a specification.

This invention relates to apparatus for extracting liquid from any material, such, for example, as oil from cotton-seed, and the object of the invention is to provide means for creating two kinds of mechanical forces upon the material, one a series of compressions, a hammering or percussive pressure to crush, macerate and compress the more solid portion of the material; and the other a centrifugal motion, to throw off the liquid expressed from the pulpy constituents.

In the illustrated and preferred embodiment of my invention, the material treated, such as cotton-seed and the like, is subjected to the rapid series of compressions successively delivered by mechanical means that will be described, while the entire mass is simultaneously acted upon by centrifugal force, generated for example by the rapid rotation of the parts carrying the material being separated.

In the accompanying drawings:

Fig. 1 is a vertical section through the entire machine;

Fig. 2 is a similar view of the upper portion of the machine on an enlarged scale;

Fig. 3 is a fragmentary sectional view of the lower portion of the machine enlarged, with certain parts in elevation;

Fig. 4 is a fragmentary side elevation of the lower portion of the machine;

Figs. 5 and 6 are end and top views respectively of the details.

Referring to the drawings, the letter A designates an outside casing, which may be of any desired form, but is shown in the drawings as made up of several castings, which I shall designate the base casting 1, the top casting 2, the hopper casting 3, and the bearing-plate 4, all of which parts are held secured together by screws 5, thus making it possible to easily dismantle the machine and put it together, or to gain access to the mechanism.

The numeral 6 is a worm shaft, held sta-

tionary by the squared lower end 7 in a hole in the bottom of the cup 8, and the latter is held in place in an orifice 9 in the casting 1 by screws 10. A removable plate 11 closes the lower end of the cup 8. The upper end of the worm-shaft 6 has a worm 12 thereon. The pan 13 is provided with a hollow stem 14, which surrounds and confines the worm shaft 6, as shown in Fig. 1. Surrounding the lower end of the hollow stem 14 is a sleeve 15. A bevel-gear 16 is secured to this sleeve 15, and this is driven by a bevel-gear 17 on the horizontal drive-shaft 18.

Journalized in the sleeve 15 are the two crank-shafts 19, and secured on these crank-shafts are worm-gears 20, which mesh with the worm 12. As the drive-shaft 18 revolves, it transmits motion through the gears 16 and 17 to the sleeve 15, and by turning them the two crank-shafts 19 are rotated by reason of the worm-gears 20 meshing with the stationary centrally located worm 12. These crank-shafts have the connecting-rods 21 connected therewith, and these connecting rods extend to the collar 22 to which the connecting-rods are connected by pins 23. A key 24 extends across through the slots 25 in the hollow stem 14, and through holes 26 in the collar 22, and is secured by a screw 27 to a central shaft 28, which not only rotates with the sleeve 15 and collar 22 but also reciprocates with the rotation of the crank-shafts 19.

The cotton-seed or other material is fed down through a hopper 29 at the top of the machine into the receiving-chamber 30 below, and the reciprocation of the shaft 28 imparts a compressing effect to the head 31 through toggles 32, thus feeding and compressing the material and forcing it up through compression chamber 33 between the outer wall of the receptacle 30 and the inner wall of the pan 13. While the dry solid material is thus being forced up through the outlet 34, through the reciprocations of the shaft 28, the liquid, such as oil, is being forced out through the vents 35 by centrifugal action into the container 36, whence it is drained off through a discharge pipe 37. The solid material is held back, and the liquid is expressed by being forced under great pressure between the rings 38 which are held in place in a recess

in the inner wall of the pan 13 by the clamping-ring 39, which latter is held solidly in place by the screws 40.

This clamping-ring 39 has an outwardly-extending flange 41, over which the solid material passes into the space in the casing 2, and thence out through the spout 42, while the liquid is confined within the container 36.

10 As a simple means of regulating the size of the outlet 34, the collar 43 has teeth 44 on its outer periphery, as well as threads 45 on its inner circumference, which screw on the threads 47 of the clamping-ring 39. This 15 collar 43 is turned by screwing the head 45 down until the opening 46 meshes with the teeth 44, when the wheel 48 is turned, thus turning the collar to the right or left to regulate the size of the outlet 34.

20 The various moving parts are surrounded by suitable ball-bearings 49, wherever they are needed as shown, and the lower ends of the toggles 32 are carried in squared blocks 50 (see Figs. 5 and 6) which have dovetailed sliding connection 51 with the upper end of the shaft 28, and bushings (such as 52) are employed wherever required.

Thus two mechanical actions are going on simultaneously, namely a compressing, due 30 to the reciprocation of the central shaft 28 with the head 31 in the receptacle 30, and a centrifugal force due to the rotations of the operating parts, all of which is mechanical as distinguished from hydraulic or other 35 pressure. This construction described is merely typical; it might, of course, be varied more or less without departure from my invention.

There might be occasions when it would be 40 desirable to operate this machine without toggles 32, for example for some materials which do not require great pressure, in which instance it might be advantageous to make the simple alteration of connecting the 45 head 31 directly to the vertical shaft 28, thereby omitting the toggles.

I claim:

1. In a structure of the character described, the combination of a pressure chamber, and means for subjecting material therein simultaneously to mechanical pressure and centrifugal action.

2. In a structure of the character described, the combination of a pressure-chamber, means for regulating the outlet thereof, whereby to determine the pressure to which the material is subjected, and mechanical means for simultaneously subjecting the material to mechanical pressure and centrifugal 60 action.

3. In a structure of the character described, the combination of a pressure chamber adapted to receive the material to be treated, mechanical means for repeatedly pounding 65 and compressing the material by reciprocating

ing action, and mechanical means for rotating the parts simultaneously with the reciprocations to cause the liquid material to be removed by centrifugal action.

4. In a structure of the character described, the combination of a pressure chamber, a pan having outlets therein, means for regulating the size of the outlet from the pan, a head, and means for reciprocating the head and rotating the head and pan, where- 75 by simultaneously to compress the material, and to separate the liquid from the material thus compressed by centrifugal action.

5. In a structure of the character described, the combination of a stationary 80 worm, a sleeve, crank-shafts journaled in the sleeve, a collar, connecting-rods extending from the crank-shaft to the collar, gears on the crank-shaft meshed with the stationary worm, a hollow stem, a shaft therein, a key 85 connected with the sleeve and shaft and having sliding connection with the hollow stem, whereby the rotation of the sleeve has the effect of reciprocating the shaft and rotating the shaft and hollow stem, a compression chamber, a pan carried at the upper 90 end of the hollow sleeve, and toggles connecting the head with the upper end of the reciprocating shaft.

6. In a structure of the character de- 95 scribed, the combination of a stationary worm, a sleeve, crank-shafts journaled in the sleeve, a collar, connecting-rods extending from the crank-shaft to the collar, gears on the crank-shaft meshed with the stationary 100 worm, a hollow stem, a shaft therein, a key connected with the sleeve and shaft and having sliding connection with the hollow stem, whereby the rotation of the sleeve has the effect of reciprocating the shaft and ro- 105 tating the shaft and hollow stem, a compression chamber, a pan carried at the upper end of the hollow sleeve, toggles connecting the head with the upper end of the reciprocating shaft, the pan having holes for 110 the discharge of the liquid by centrifugal action, an outlet for the solid material, means for regulating the size of the outlet, rings clamped in the inner wall of the pan, and a clamping-ring for holding the rings 115 in place and having a flange over which the solid material is fed, and which prevents the escape of liquid material separated.

7. In a structure of the character de- 120 scribed, the combination with a pressure- chamber, a head, a rotary hollow shaft, a rotary pan having a hollow stem, a shaft reciprocating within the hollow stem, toggles connecting the shaft with the head, and means for reciprocating the head and 125 shaft and for simultaneously rotating the pan, head and shaft.

8. In a structure of the character de- 130 scribed, the combination with a pressure-chamber, a head, a rotary hollow shaft, a

rotary pan having a hollow stem, a shaft reciprocating within the hollow stem, toggles connecting the shaft with the head, means for reciprocating the head and shaft and for simultaneously rotating the pan, head and shaft, a collar threaded at the upper end of the machine and having teeth on its outer periphery, a gear, and means for causing the gear to mesh with the teeth of the collar, whereby the latter is turned to regulate the size of the outlet from the pan.

In testimony whereof I hereunto affix my signature.

ABRAM S. KIRSHNER.
